UNITED STATES PATENT OFFICE.

DAVID B. WESTON, OF SHARON, MASSACHUSETTS.

CENTRIFUGAL SEPARATOR.

1,279,057.

Specification of Letters Patent. Patented Sept. 17, 1918.

Application filed November 15, 1913. Serial No. 801,155.

To all whom it may concern:

Be it known that I, DAVID B. WESTON, citizen of the United States, and resident of Sharon, county of Norfolk, State of Massachusetts, have invented certain new and useful Improvements in Centrifugal Separators, of which the following is a specification.

This invention relates to centrifugal machines intended for use in clarifying liquids by separating the solid content therefrom by centrifugal action. The invention is particularly applicable for use in clarifying cane juice in place of the filter presses commonly used to extract the dirt or sediment from the cane juice, thus avoiding the slow process of filtration and the frequent clogging-up of the filter bags or screens.

The invention comprises generally speaking, a centrifugal receptacle provided with openings in its bottom for the discharge of the solid matter extracted and having an annular top covering the peripheral portion of the receptacle over the inside edge of which the clarified liquid escapes, combined with means for introducing the liquid to be treated into the peripheral bottom portion of the receptacle, and a baffle plate in the upper portion of the receptacle extended inwardly beyond the inside edge of the top, so as to prevent the direct flow of the sediment-containing liquid to the outlet before the sediment has been separated therefrom.

Another feature of the invention consists in means for detachably securing the deflector ring in the bottom portion of the receptacle, so that it may be removed from operative position in order to give the attendant free access when discharging the solid content through the openings in the bottom of the receptacle. Another feature of the present invention consists in the arrangement of the inlet pipe to deliver the liquid to be treated through the bottom of the receptacle into the interior.

These and other features of the invention will be fully described in this specification and will be defined in the claims forming part thereof.

In the drawings I have illustrated some

of the simpler forms embodying the principles of this invention. 50

Figure 1 is an elevation in central section of a suspended centrifugal containing my improvements;

Fig. 2 is a plan view in section showing 55 the construction for detachably holding the deflector in place;

Fig. 3 illustrates a modified construction for holding the deflector ring in place;

Fig. 4 is a side elevation of the same; and 60

Figs. 5 and 6 illustrate still another form of means for detachably fastening the deflector or spreader member in position.

In the drawings, I have illustrated the invention applied to a centrifugal machine 65 comprising a cylindrical receptacle *a* suspended from an overhead support by a gyroscopic rotary shaft *a'* to whose lower end is secured a radial armed spider *a''* carrying the bottom or floor *a'''* of the receptacle. 70

The bottom of the receptacle is downwardly inclined toward the center of the machine and is continued some distance beyond the periphery of the spider, as shown at *a''*, so as to leave space above its lower edge for 75 an inlet or supply pipe *b* through which the liquid to be treated is conducted to the interior of the rotating receptacle. The outlet or nozzle of the pipe *b* is, of course, directed outwardly, and the centrifugal force, 80 due to the rotation of the receptacle, causes liquid to flow up between the arms of the spider and beneath the deflector ring *c* to the peripheral wall of the receptacle.

The peripheral portion of the receptacle 85 is covered at the top by an annular top or cover *a'''* which acts as a dam or barrier to hold back the solid matter extracted as it walls-up against the peripheral wall of the receptacle, while allowing the clarified 90 liquid to escape over its inner edge after the wall of liquid is built into a sufficient thickness to flow around this inside edge. A flanged hood or ring *a''''* located a slight distance above and inside of the inner edge of 95 the top *a''''* serves to deflect the clarified liquid outwardly into the surrounding curb.

The receptacle is provided with a series

of vertical radially arranged wings or dia-
phragms *d* projected inwardly from the pe-
ripheral wall, preferably extending from
top to bottom of the receptacle.

5 As the most efficient work is secured by
conducting the liquid introduced directly to-
ward the periphery of the receptacle, I pro-
vide a deflector ring *c*, which is detachably
held in place in the lower part of the re-
ceptacle.

10 According to the form shown in Fig. 2,
this ring *c* is made in sections, one to each
compartment included between adjacent
wings of the machine. Each wing is pro-
15 vided at its inside edge, near the bottom,
with a pair of supporting plates *c'* on oppo-
site sides of the wing, and as in this form it
is intended to remove each section by draw-
ing them toward the center of the basket, the
20 plates are formed with wedge-shaped raised
ledges *c²* forming diagonal shoulders against
which the correspondingly oblique end por-
tions of the ring sections may abut, to pre-
25 vent their being thrown outwardly from po-
sition by centrifugal force when the machine
is rotating. The plates are also provided
with undercut lugs or hooks which over-
hang the outer corners of the ring sections
30 to prevent the outer edge from lifting. The
inner edges of the plates are detachably
locked in place by means of the swinging
latches or dogs *c⁴* which are slotted to fit
over the respective wings by which they are
35 pivotally supported. To remove a section
the operator has merely to grasp the inner
edge thereof raising the latch or dog *c⁴*, then
drawing the section inwardly toward the
center of the machine. After the deflector
40 has thus been removed, he has free access
to the compartment for the purpose of
scooping out, through the bottom, the solid
matter walled-up on the inside of the pe-
ripheral wall. After such discharge the
45 section ring *c* may be replaced and the ma-
chine started for another run.

In Figs. 3 and 4, I have shown a some-
what different construction for fastening
the ring sections in place. In this case there
are upper angle plates *c'* arranged some
50 distance above the supporting plates *c'* and
between said upper plates *c'* and the ring
section *c*, I insert a wedge plate or key *c⁵*
which serves to hold the adjacent ends of the
ring sections firmly seated in position. As
55 shown in Fig. 3, these plates are slotted mid-
way of their sides, so as to pass beyond the
inside edge of the supporting wing.

A slightly modified form of wedge is
shown in Figs. 5 and 6. In that case the
60 section rings *c¹⁰* instead of having their rear
corners cut away to permit removal in-
wardly, are cut away slightly in front of the
inside edge of the wing, as shown at *c¹¹*, to

permit the removal of the deflector section
outwardly. In this case each deflector sec-
tion is supported on underlying angle plates
65 *c¹²* and are wedged in place by means of a
slotted key *c⁸* passed between the top of the
adjacent sections and the superimposed
angle plates *c¹³*.

The underlying angle plates *c¹²* have
turned-up lugs *c¹⁴* at their outer ends to hold
the sections against outward movement when
the machine is running, but in removing the
70 sections the outer edges may be lifted up
over these edges when the key is withdrawn.

It will, therefore, be seen that provision
may be made for removing the deflector ring
75 over toward the center or the outside of the
machine, when it is desired to get them out
80 of the way for the purpose of discharging
the solid matter.

The action of the machine is as shown.
The raw liquid being introduced through
85 pipe *b*, is deflected along the bottom of the
receptacle to the outside wall against which
it walls-up under centrifugal action. In this
position the solid matter being heavier sepa-
rates against the outside surrounding wall
90 of liquid, the lighter or clarified portions of
which tend to seek the innermost position.
When there has been sufficient accumula-
tion of liquid to reach the line of the outlet
95 in the top of the receptacle, the light or
clarified liquid escapes over the top into the
curb leaving the solid residuum walled-up
inside the receptacle. The baffle plate *e* acts
to prevent any direct flow of the newly in-
100 troduced unclarified liquid to the outlet ori-
fice, since all escaping liquid must pass
around the outside edge of this baffle plate *e*
before escaping through the top of the re-
ceptacle.

What I claim is:

1. In a centrifugal separator, the combi-
nation of a rotary receptacle provided with
105 annular top and bottom members covering
the peripheral zone of the receptacle, an an-
nular plate arranged at a distance from the
peripheral wall and adjacent to the bottom,
110 a liquid feed pipe arranged to project
through the bottom to deliver liquid into the
space between the said annular plate and
the bottom when the receptacle is rotated,
and means for detachably holding said plate
115 in its operative position and allowing it to
be raised to facilitate the discharge of the
solid separated matter through the bottom
opening, substantially as described.

2. In a centrifugal receptacle the combi-
nation with the internal radial wings, sup-
porting plates secured thereto, an annular
120 sectional deflector resting upon said sup-
porting plates adjacent to the bottom, and
retaining devices for detachably locking said
125 annular plates in position so as to permit

their removal to facilitate the discharge of solid matter through the bottom of the receptacle, substantially as described.

3. In a centrifugal receptacle the combination of the internal radial wings, supporting plates secured thereto, a sectional deflector resting upon said supporting plates, and pivotal latches adapted to engage and removably hold said deflector sections

against the supporting plates, substantially as described.

In witness whereof I have subscribed the above specification.

DAVID B. WESTON.
